UNITED STATES PATENT OFFICE

FERDINAND E. KLING, OF NEW YORK, N. Y.

APPARATUS FOR CLEANING HATS

Application filed March 17, 1930. Serial No. 436,440.

This invention is directed to an improved method of an apparatus for cleaning hats, wherein the hat is subjected to the action of a dry cleaning agent under pressure.

5 The method of the present invention is the utilization of a dry cleaning agent, as sand, which is directed onto the hat with selective pressure and while the hat is being rotated, with the effect to not only remove dirt and 10 spots from the surface, but also produce a mild pouncing effect.

The apparatus with which the present invention is particularly concerned is designed with a view to carrying out the method, and 15 includes a casing in which the hat is mounted for more or less rapid rotation, and a nozzle, controlled from the exterior of the casing, through which sand is delivered under any desired pressure. The operation is visible 20 to the operator, who can direct the nozzle as required for effective cleaning.

An essential object of the present method and apparatus is the provision of means whereby the hat may be cleaned by a dry 25 cleaning agent, to thus avoid the disadvantages of the usual wet cleaning, which as well known tends to rub the surface dirt into the body of the hat, generally results in a loosening of the fur of the hat material 30 under the necessary rubbing, and requires reshaping of the hat after cleaning, as the wet process necessarily destroys the shape of the hat.

A further object is the provision of an 35 apparatus wherein the dry cleaning material is recovered within the apparatus and continually reused for cleaning, thereby materially reducing the cost of the operation, as compared to the wet cleaning process.

40 The invention is illustrated in the accompanying drawing, in which:

Fig. 1 is a front elevation of the apparatus, the lower portion of the front wall being omitted to illustrate the operating parts.

45 Fig. 2 is a vertical central section, certain parts being shown in elevation.

Fig. 3 is a plan view of the apparatus.

Fig. 4 is an elevation, partly in section of the means for supporting the hat in inverted 50 position for cleaning.

The improved apparatus includes a casing of appropriate size, as at 1, the rear portion of the side walls 2 of which are rearwardly convergent, so that the width of the rear wall 3 is materially less than that of the front wall. The front wall, throughout the upper portion is formed with an opening to be closed by a glass door 4, serving as a means for introducing and removing the hats, and as a means to permit the operator to observe 55 at all times the cleaning operation.

The bottom of floor of the casing is in the form of a partition 5, with its forward upper edge securing to the frame of the casing immediately below the door opening, and from 60 which the partition extends downwardly and rearwardly throughout the full interior of the casing. The rear edge of the partition terminates short of the rear wall 3, where it is extended as a depending section 6, in parallel relation to the rear wall 3, the sides and bottom of the relatively narrow pocket 7 thus formed being closed, except for a door-closed opening 8, through which the material may 65 be removed when too soiled for further use.

70 A motor 9 is mounted on a transverse strut 10, connected in the frame structure below the partition 5. The energization of the motor is controlled through the usual switch (not shown) and operates a power wheel 11, through a belt 12, the power wheel being mounted on a rising brace 13 connected at the upper end to the bottom of the partition 5. The power wheel, through reduced belt 75 drive 14, operates a pulley 15, supported in a bracket 16, the shaft of which pulley carries a bevel gear 17.

80 A drive shaft 18 is mounted at its lower end in the bracket 16, is provided with a bevel gear 19 in mesh with the gear 17, this power shaft extending through and above the partition 5. The drive shaft at the point of extension through the partition is provided with a suitable protecting gland and mounting 85 20, of any suitable type, the purpose being to guide and support the drive shaft and prevent the sand from reaching the shaft or flowing through the partition at this point.

90 A table 21 is removably supported on the upper end of the drive shaft, the connection, 100

while permitting free separation of the table insuring rotation of the table with the drive shaft. A hat form is removably secured on the table, including the usual brim ring or support 22 and the hat or crown block 23.

5 These parts may be separably connected to each other and to the table by pins 24, carried by one part and seated in appropriate holes in the cooperating part. Thus the hat form is designed to be rotated by the drive shaft.

10 A nozzle guide is secured in the upper portion of the casing above the partition 5. This guide comprises parallel bars 25, connected at their upper ends to the top of the casing, and extended downwardly therefrom on slightly curved planes to a point on one of the side walls somewhat above the table 21. A nozzle 26, which preferably comprises a nozzle outlet 27 of appropriate form and a mixing body 28 is mounted for movement vertically of the guide bars 25, there being spaced rollers 29 on each side of the body 28 to slidably embrace each of the guide bars. 15

20 The nozzle is supported and operated through a rod 30 secured to the body 28 and extending upwardly through the top of the casing, where it is connected to a hand lever 31, pivotally mounted on the casing top, and operable as obvious to control the nozzle. 25

30 The guide bars 25 are connected near their lower ends by a cross strip 32, which when engaged by the nozzle body causes a forward tipping of the nozzle end, for a purpose which will later appear.

35 A flexible conduit 33 leads from the pocket 7 through the side wall of the casing and is connected to the nozzle body 28, thus delivering the dry cleaning agent, as sand, to the nozzle body. An air pressure conduit 34, leads from any suitable source of air under pressure to the nozzle body 28, a manually operable valve controlling the pressure, as at 35.

40 In reversing the hat for cleaning the under side of the brim, as will later appear, the hat form is removed and a flanged box 36 is applied to the table 21, in which the hat is placed in reversed order, a block of wood or cork being inserted to prevent the sand from entering the hat.

45 In the use of the apparatus, after assembling the form sections 22 and 23 on the table 21, the hat is placed over the crown form so that the rim rests on the rim section 22, the motor is started, air under pressure to the desired extent admitted through the conduit 34, and the sand which has been previously placed in the pocket 7 is drawn upwardly through the conduit 33, mingled with the air in the nozzle body 28, and projected through the nozzle 27 in the form of a fine stream of sand moving under considerable pressure. 50

60 The nozzle is manipulated lengthwise of the

guideways by the hand lever 31, a stream of sand being directed onto the hat crown in order to create the necessary cleaning action of the material. When the nozzle has been lowered to a position to reach the upper surface of the brim of the hat, the nozzle contacts with the strip 32 and is tilted downwardly to more conveniently direct the stream of sand onto the brim. 70

75 After cleaning in this manner, the hat is reversed in the flanged box 36 and the latter placed on the table 21, the forms 22 and 23 having been removed. The interior of the hat is massed against the sand by any suitable filler, as a block of cork, wood or the like fitted within the hat. The bottom or under surface of the hat brim is now exposed and may be subjected to the abrading action of the sand for cleaning by effective manipulation of the nozzle. It will, of course, be understood that the sand, immediately following contact with the hat for cleaning purposes, falls onto the partition 5, down which it gravitates to the pocket where it is continually reused for cleaning operations. 80

85 Thus as long as the sand remains sufficiently clean, it may be continually reused for successive hat cleaning operations and need be replaced only when unfit for further cleaning. 90

95

100 This method has many advantages over the usual hat cleaning processes. In the first place, the present method is a dry method, permitting the hat to retain the shape by indicated folds in which the owner prefers to have it so that, after cleaning, the hat may be returned in this shape. In the wet cleaning processes, the hat is subjected to more or less saturation with cleaning fluids, usually of a highly inflammable nature, and subjected to rubbing. This not only has a tendency to force the dirt into the fabric of the hat rather than eliminate the dirt, but also entirely destroys the original shape of the hat, that is the shape in which it is worn, and the hat has to be reshaped. This is usually a difficult step, in that generally the owner has his individual way of shaping his hat and the cleaner very rarely is able to replace this shape when reshaping the hat after wet cleaning. Furthermore, in the present process the nozzle may be held at any particular point on the hat where an unusual condition requires a longer cleaning operation, and those portions of the hat which are fairly clean need be subjected but momentarily to the sand. Thus the operator may readily control the cleaning operation in directing the sand with the greatest effectiveness at the desired point or points and insuring that all of the surface of the hat may be effectively and quickly brought to practically its original state of cleanliness. 110

115 Of course, the trimming, as the external band of the hat, may be protected in any ap- 120

125

propriate way during the cleaning operation. Thus, for example, a rubber band of appropriate width may be placed over the hat band to protect the same against the influence of the sand.

The use of sand under pressure, in addition to thoroughly and effectively cleaning the hat, has a mild pouncing effect which thus tends to renew the life of the fur. Thus the operation is in effect a practical restoring of the hat to its original condition, for not only is the hat effectively cleaned but practically refinished incident to the mild pouncing effect in the use of the sand under pressure.

What is claimed as new is:—

1. An apparatus for cleaning hats including a casing, a hat form rotatable therein, nozzle guides carried by the casing, a nozzle movable longitudinally of the guides, a source of communication between the nozzle and a supply of sand, a source of communication between the nozzle and a supply of air under pressure, means operative from beyond the casing for moving the nozzle lengthwise of the guides, and means carried by the guides for tilting the nozzle at a determined point in the movement of the nozzle.

2. An apparatus for cleaning hats including a casing, a hat form rotatable therein, guides within the casing, a nozzle movable longitudinally of the guides, a sand pocket formed in the casing, a conduit communication between the sand pocket and nozzle, means for admitting air under pressure to the nozzle, and means operative from beyond the casing for moving the nozzle longitudinally of the guides to direct sand under pressure onto a hat on said form.

3. An apparatus for cleaning hats including a casing, a hat form rotatable therein, guides within the casing, a nozzle movable longitudinally of the guides, a sand pocket formed in the casing, a conduit communication between the sand pocket and nozzle, means for admitting air under pressure to the nozzle, means operative from beyond the casing for moving the nozzle longitudinally of the guides to direct sand under pressure onto a hat on said form, and means carried by the casing for directing the sand beyond the hat back into the pocket.

4. An apparatus for cleaning hats including a casing, a hat form rotatable therein, guides within the casing, a nozzle movable longitudinally of the guides, a sand pocket formed in the casing, a conduit communication between the sand pocket and nozzle, means for admitting air under pressure to the nozzle, and means carried by the guide to tilt the nozzle at a predetermined point in the movement of the guide for directing the stream of sand onto the brim of a hat on the form.

5. An apparatus for cleaning hats, including a casing, a rotatable hat form therein, a

sand delivering nozzle arranged for moving within the casing and directing sand under pressure toward the hat form, a guide for the nozzle, and a stop on the guide to cooperate with the nozzle at a predetermined point in its guided movement to change the sand-directing path of the nozzle, and manual means for controlling the nozzle movement.

6. An apparatus for cleaning hats including a rotatable hat form, a nozzle for delivering sand under pressure toward the hat form, and guides along which the nozzle is moved during sand delivery, said guides being formed at a determinate point with means to engage and provide for tilting of the nozzle.

In testimony whereof I affix my signature.
